UNITED STATES PATENT OFFICE.

LEWIS HALLOCK NASH, OF SOUTH NORWALK, CONNECTICUT.

DESIGN FOR A WATER-METER.

SPECIFICATION forming part of Design No. 31,248, dated July 18, 1899.

Application filed February 16, 1899. Serial No. 705,726. Term of patent 14 years.

To all whom it may concern:

Be it known that I, LEWIS HALLOCK NASH, a citizen of the United States, and a resident of South Norwalk, in the county of Fairfield and State of Connecticut, have invented a certain new and useful Design for Water-Meters, of which the following is a specification.

In the drawings, Figure 1 shows in elevation a water-meter involving my design, and Fig. 2 is a top view of the same.

As shown in the drawings, the leading and essential feature of this design consists of a water-meter the body or case whereof is elongated in the direction of its axis, tapering from the middle of its length toward its two ends and surmounted by a crown at its greatest diameter. The body or case A of the meter

consists of two conical parts of cylindrical form joined at their bases, each end terminating in a non-tapering cylindrical extension 20 B B. At the bases of the two cones the crown-shaped casting C, of circular form, sets in horizontal fixed relation to the cones and forms the top of the meter.

Having described my invention, what I claim as new, and desire to secure by Letters Patent, is—

The design for a water-meter herein shown and described.

LEWIS HALLOCK NASH.
